UNITED STATES PATENT OFFICE.

FRANK A. WELLS, OF NEW YORK, N. Y.

DESIGN FOR A BATH-TUB.

SPECIFICATION forming part of Design No. 32,858, dated June 19, 1900.

Application filed May 25, 1900. Serial No. 18,007. Term of patent 7 years.

To all whom it may concern:

Be it known that I, FRANK A. WELLS, a citizen of the United States, and a resident of New York city, borough of Manhattan, New York, have invented and produced a new and original Design for Bath-Tubs, of which the following is a specification, reference being had to the accompanying drawings, forming part hereof, wherein—

Figure 1 is a side elevation of a bath-tub embodying my design, and Fig. 2 is a transverse section thereof.

The essential feature of my design consists in a bath-tub having its outer surface embellished by a flaring rim at its open top, a convexly-curved surface below the rim, and a flange below said surface, the general surface contour being substantially in double-ogee form, extending vertically.

In the drawings the letter A indicates the bath-tub, at the top of which is the flaring rim *a*, the central convexly-curved outer surface below the rim being denoted by the letter *b*, the flange below said surface being lettered *c*. The outer surface is concave at *d* between the convex surface *b* and the rim *a* and flange *c*. The rim *a*, flange *c*, and intermediate curved surfaces extend symmetrically around the tub, and in a vertical direction the general surface contour is substantially in double-ogee form.

What I claim is—

The design for a bath-tub, substantially as herein shown and described.

FRANK A. WELLS.
